AUTOMATIC BOWLING MACHINE

James J. Sunday, Detroit, Mich.

Application November 30, 1955, Serial No. 549,952

7 Claims. (Cl. 273—44)

This invention relates to a bowling machine and particularly to a bowling machine of a miniature type for playing a modified type of bowling game using bowling balls and bowling pins of a smaller size than those conventionally used in standard bowling alleys.

In a bowling machine of this type, the pins are normally held in position on the alley by magnets and are provided with cords extending upwardly over pulleys and having individual weights on each cord adapted to lift the pins off the alley and hold them in an elevated position when they are struck by the ball.

It is an object of this invention to provide a novel apparatus for setting the pins in playing position on the alley wherein said apparatus is manually operated by the operator and is provided with means for boosting the manual action of the operator.

It is a further object of the invention to provide such a pin-setting apparatus wherein the force with which the pins are set in position on the alley is controlled.

It is a further object of the invention to provide a novel ball-return apparatus adapted to return the ball to the player automatically.

It is a further object of the invention to provide a novel supporting structure for the pin-setting apparatus and the ball-return apparatus.

It is a further object of the invention to provide a novel means for operating the ball-return apparatus.

Basically, the machine includes an alley having a player's station at one end and a pin-setting apparatus and a ball-return apparatus at the other end. The pin-setting apparatus and ball-return apparatus are mounted on a frame generally overlying the pin-supporting area of the alley. The pin-setting apparatus includes a platen positioned above the pins and having a multiplicity of openings through which the cords attached to the pins extend. The platen is vertically reciprocable. A linkage is provided which extends to the player's station whereby, when the player actuates the linkage, the platen is lowered for resetting the pins. Weights are attached to the linkage tending to move and maintain the platen in its uppermost position. The linkage for lowering the platen includes a belt adapted to contact a continuously rotating pulley when the linkage is actuated by the operator, thereby boosting or enhancing the manual actuation by the operator. In addition, a dash pot mechanism is attached to the linkage for controlling the rate of lowering of the platen.

The size of the openings in the platen through which the cords extend is smaller than the largest diameter of the pins whereby the pins are forced downwardly when the platen is lowered bringing them into position on the alley.

The ball-return apparatus is mounted at one side of the alley and includes an upwardly inclined chute which is maintained in spaced relationship with an upwardly inclined belt. The chute is provided with springs which permit limited movement of the chute away from the belt. After the ball strikes the pins, it rolls to the rear

2

of the alley and down a transversely inclined ramp to a position between the inclined chute and the belt. Movement of the belt causes the ball to roll upwardly along the inclined chute and thereafter downwardly along a track which extends alongside the alley to the player's station.

In the drawings:

Fig. 9 is a fragmentary plan view of the platen for resetting the pins taken along the line 9—9 in Fig. 7.

Fig. 10 is an elevational view of the ball-return apparatus.

Fig. 11 is a sectional view taken along the line 11—11 in Fig. 10.

Fig. 12 is an elevational view of the drive mechanism.

Fig. 13 is a sectional view taken along the line 13—13 in Fig. 12.

As shown in Fig. 1, the bowling machine comprises a longitudinally extending, substantially horizontal alley 20 at the forward end of which is a player's station 21 and at the rear end of which is a housing 22 containing a pin-setting apparatus and a ball-return apparatus. A control panel 23 is located at the player's station. A coin-operated switch mechanism 25 and a pin-setting lever 24 are mounted on the control panel 23 for controlling the bowling machine as hereinafter described.

Extending on either side of the alley 20 and parallel thereto are gutters or troughs 26 (Figs. 1, 5). Pin-setting apparatus 28 and ball-return apparatus 29 are mounted within the housing 22 on a frame 36 (Fig. 3). The pin-setting apparatus 28 overlies a pin-setting area 30 at the rear end of the alley 20.

The housing 22 comprises a top panel 31, side panels 32, 33, a rear end panel 34 and a front end panel 35. The front panel 35 is open at the bottom thereof overlying the alley to permit the bowling ball to roll along the alley and also to permit visibility of the pins from the player's station. The housing 22 surrounds the frame 36 which supports the pin-setting apparatus 28 and the ball-return apparatus 29. As shown in Fig. 3, the frame 36 is preferably made of a series of angle members and comprises front upright members 37, 38 connected to rear upright members 39, 40 by horizontal side members including upper side members 41, 42, intermediate side members 43, 44 and lower side members 45, 46. The front uprights 37, 38 are connected to each other by a horizontal front end member 47 and the rear upright members 39, 40 are connected to each other by an upper horizontal rear end member 48 and intermediate horizontal rear end member 49. Transverse top member 50 extends between the upper side members 41, 42 while transverse bottom members 51, 52 extend between the lower side members 45, 46.

The frame 36 is mounted at the rear of the alley and a pin-supporting platform 53 is mounted on the bottom members 51, 52 (Fig. 7). A layer 54 of hard rubber or other scuff-resistant material is provided over the pin-supporting platform 53. A multiplicity of magnets 55

are embedded in the pin-supporting platform 53 and are adapted to be engaged by metal inserts 56 in the lower ends of the pins 57. The pins 57 are thus releasably engaged with the magnets 55.

A cord 58 extends upwardly from the upper end of each pin 57 over a pulley 59 fixed on shaft 60 which is rotatably mounted between cross members 61, 62 on the upper members 47 and 50 (Figs. 5, 7). A weight 63 is attached to the end of each cord 58 and thereby places an upward force on the pin 57 which pulls the pin 57 upwardly off the alley when a bowling ball strikes the pin and knocks it out of engagement with the magnet 55.

The pulley 59 for the pin nearest the player's station is fixed on a short shaft rotatably mounted on a bracket 79 extending forwardly from the front end member 47 (Fig. 7).

A vertically reciprocable platen 64 is mounted above the pin-supporting platform 53 and includes a multiplicity of openings 65 through which the cords 58 extend (Figs. 7, 9). The vertical movement of the platen 64 is guided by vertical guide bars 66 which engage rollers 67, 68 rotatably mounted on short longitudinally extending members 69, 70 and 71, 72, respectively (Figs. 3, 7). The members 69, 70, 71 and 72 are mounted in vertically spaced relationship below cross members 61, 62 by short downwardly extending, vertical supports 73, 74, 75 and 76. A short brace 77 extends between the lower end of the vertical member 74 and the upright 37 and another short brace 78 extends between the lower end of the vertical member 76 and the upright 38.

As shown in Figs. 2 and 7, the movement of the platen 64 is controlled by a linkage including a pair of links 80 pivotally connected at one end thereof to a bracket 81 on each vertical guide bar 66 (Fig. 8) and pivotally connected at the other end thereof to an arm 82. The arms 82 are fixed at the other end thereof to a shaft 83 which is rotatably mounted on bearings 84, 85 which are fixed on vertical members 73, 75 respectively of the frame 36.

The platen 64 is normally yieldably maintained in its uppermost position by means of a weight 86 connected to the shaft 83 by a weight arm 87 extending rearwardly of the shaft. The weight is of sufficient size to yieldingly urge the platen 64 toward its uppermost position. The platen 64 is lowered by a linkage including a lever 88 fixed at one end to the shaft 83 and pivotally connected at the other end to a pair of connecting members 89 which are also pivotally connected to a lever bar 90. The lever bar 90 is pivotally mounted above the lever 88 at a point intermediate its ends to a short shaft mounted in a bearing 91 which is fastened to vertical member 73.

A cord 92 is connected to the other end of the lever bar 90 and passes downwardly past a pulley 93 and is trained over a pulley 94 mounted in the alley (Fig. 5). The cord extends forwardly under the alley to a pulley 95 mounted at the player's station 21 and is trained over the pulley 95 and connected at the other end thereof to the pin-setting lever 24. The pin-setting lever 24 is pivoted in such a manner that by pulling the pin-setting lever, the cord 92 is also pulled, causing the lever bar 90 to rotate about its pivot point and, in turn, rotating the shaft 83 in such a manner that the arms 82 are moved to force the platen 64 to move downwardly.

In order to facilitate the movement of the platen 64 downwardly, the pulley 93 is preferably continuously rotated, in a counterclockwise direction as viewed in Fig. 2, with the cord 92 contacting said pulley 93 loosely. When the lever 24 is pulled, the cord 92 is caused to frictionally engage the rotating pulley 93 and provide a boosting movement in the direction of the pulling action of the operator on the lever 24. The portion of the cord 92 which contacts the pulley 93 is preferably a V-belt in order to provide a better frictional engagement with the pulley 93.

Inasmuch as the boosting force supplied by the pulley 93 will depend upon the degree of frictional engagement,

the boosting force will vary with the force used by the operator to pull the lever 24. In order to control the force with which the platen is lowered, a dash pot 96 is preferably mounted on the lower end member 49 (Figs. 2, 3 and 7). The dash pot 96 is provided with an arm 97 pivotally connected to a link 98 which, in turn, is pivoted to weight arm 87. When the hand lever 24 is pulled to lower the platen, the dash pot 96 tends to oppose the downward movement of the platen. The rate at which the platen 64 is forced downwardly cannot exceed a predetermined amount as controlled by the dash pot. The cord 92 is provided with a turn buckle 99 for adjusting the length thereof (Figs. 1, 2). In order to limit the upward movement of the platen, a chain 100 (Fig. 7) is provided and extends between the weight 86 and a small spring 101 connected to upper end member 48. The chain 100 thus limits the upward movement of the platen while the spring 101 insures that any shock involved in the movement of the platen to its uppermost position will be absorbed.

In order to insure the accurate centering of the bowling pins in the openings 65 when the platen is moved downwardly, a layer 102 of resilient material such as rubber is provided on the undersurface of the platen 64 and includes a multiplicity of openings 103 in axial alignment with the openings 65 (Figs. 7, 9). The openings 103 in the layer 102 are smaller than the openings 65 in the platen 64 thereby providing an annular lip 104 of resilient material surrounding each opening 65 and capable of being flexed upwardly when the platen is lowered to engage the sides of the pin 57.

Referring to Figs. 4, 6 and 7, a back stop 105 is positioned at the rear of the bowling machine and includes a downwardly sloping section 106 which extends from the pin-supporting area toward the rear to a transverse ramp 107. The transverse ramp 107 is inclined downwardly to one side of the machine for guiding the bowling ball to the ball-return apparatus after the ball has struck the pins. The back stop 105 includes sides 108, 109 and a deflector 110 positioned over the transverse ramp 107 and inclined upwardly toward the front of the machine at an angle of preferably less than 30° with the horizontal. The deflector 110 directs the bowling balls downwardly onto the transverse ramp 107.

A bumper 111 of thick resilient material may be positioned transversely across the rear of the stop 105. The various surfaces of the back stop with which a ball may come into contact are preferably provided with a layer 113 of scuff-resistant material such as a hard rubber. The side wall 108 of the back stop 105 is provided with an opening 112 for permitting the passage of the bowling ball to the ball-return apparatus as it rolls down the transverse ramp 107.

Referring to Fig. 10, the ball-return apparatus 29 comprises a bracket 120 including parallel inclined upwardly and forwardly extending members 121 and parallel slightly inclined, upwardly and rearwardly extending members 122. The bracket 120 is fastened to the frame 36 at 123 on side member 45 by a bolt passing through a brace 124 and at 125 on side member 43 by a bolt passing through a short brace 126. A small pulley 127 is rotatably mounted on the members 122 and larger pulleys 128, 129 are rotatably mounted at either end of the members 121.

An endless belt 130 is trained over the pulleys 127, 128, 129. Tension on the belt is maintained by a roller 131 contacting the belt and held in engagement therewith. The roller is rotatably mounted on a short arm 132 pivotally connected at 133 to a short bar on the member 121. A tension spring 134 extends between the free end of the arm 132 and the member 121 yieldingly urging the roller 131 in position against the belt. A fixed support 135 extends downwardly from the members 122 and comprises spaced parallel legs 136 and a cross piece 137 extending between the lower ends of the legs 136 (Fig. 75).

11) Reinforcing struts 138 extend diagonally between the members 122 and the legs 136. A support 139, similar to support 135, is mounted near the upper end of the members 121.

The supports 135, 139 serve to mount a chute 140 which has a slightly downwardly inclined portion 141 and an upwardly inclined portion 142. The ends of the chute are mounted on the brackets 135, 139 by bolts 143, 144. The bolts are of such length that the chute 140 has limited movement away from the belt 130. The chute is maintained in its innermost position relative to the belt at one end by tension springs 145 extending between the chute 140 and the reinforcing struts 138 (Fig. 11) and at the other end by tension springs 146, 147 extending between the reinforcing struts 138 of the bracket 139 and the other end of the chute 140. A short chute section 148 is pivotally connected to the upper end of the chute 140 and serves as a kicker as presently described.

Tension springs 149 extend between the end of the chute section 148 and points on short bars 150 mounted on the upper members 121. The springs 149 yieldingly urge the short chute section 148 inwardly toward the belt 130. A plate 114 is fastened to the bracket 120 by short bars 115 in position in back of the reach of the belt 130 adjacent the inclined section 142 of the chute 140. A downwardly and forwardly inclined track 180 extends from the top of the short chute section alongside said alley to the player's station 21 (Fig. 1).

When a ball rolls down the alley, strikes the pins and thereafter rolls down the inclined section 106 to the transverse ramp 107, it is guided by the transverse ramp 107 through the opening in the wall 108 (Fig. 4) to a position on the short inclined section 141 of the chute underlying the belt 130. The ball then rolls down the short section 141 where it is gripped between the belt 130 and the chute 140. The lower end of the chute 140 may thereupon yield, permitting the chute 140 to move outwardly against the action of the springs 145.

As the belt 130 rotates, it causes the ball to roll up the chute 140. Frictional engagement between the belt 130, chute 140 and the ball is maintained by the tension of the springs 146, 147 which permit the chute to yieldingly move outwardly away from the belt. As the ball is carried to the upper end of the inclined section 142 of the chute 140 onto the short section 148, it moves the short section 148 outwardly away from the belt. Further movement of the ball will bring it into position adjacent the upper end of the track 180 on which it will roll downwardly toward the player's station 21 (Figs. 1, 7). As the ball moves past the end of the short chute section 148, the spring 149 will cause the chute section to move inwardly toward the belt providing an additional kick to the ball to insure its passage over onto the downwardly inclined track 180.

The belt 130 is driven by a pulley 151 mounted on the shaft 152. The pulley 93 of the pin-setting apparatus is also mounted on the shaft 152 (Fig. 5). The drive mechanism to the pulley 151 is shown in Figs. 12 and 13. An electric motor 153 is mounted on a plate 154 secured to arms 181, 182 which, in turn, are pivotally connected to vertical bars 155, 156 extending between the upper and lower end members 48, 49 on the frame 36 (Fig. 3). The arms 181, 182 pivot about a horizontal axis.

A short cross bar 183 extends between the outer ends of the arms 181, 182 and is provided with an opening through which a bolt 157 extends. The bolt is fixedly mounted in vertical position on a fixed horizontal bracket 158 extending inwardly from the vertical bars 155, 156 (Fig. 3). Nuts 159, 160 are threaded on the bolt 157 above and below the plate 183 in order to adjust the pivotal position of the plate 183. A pair of spaced arms 161, 162 are pivotally connected on horizontal bracket 156 for movement about a horizontal axis. The arms

161, 162 extend downwardly and a plate 164 is mounted between the arms. Journals 165, 166 are, in turn, mounted on the plate 164 and serve to rotatably support a shaft 168. The position of the plate 164 may be adjusted by a bolt 169 mounted on a short cross piece 170 which extends horizontally between the vertical bars 155, 156. The bolt passes through a vertically elongated slot 171 in the plate 164. Nuts 172, 173 which are threaded on either side of the plate 164 serve to adjustably locate the position of the plate 164. A large pulley 177 is mounted on one end of the shaft 168 and a small pulley 178 is mounted on the other end of the shaft 168. A belt 175 is trained over the pulley 176 of the motor and the large pulley 177 in alignment therewith. A belt 179 extends between the pulley 178 and the large ball-return pulley 151.

By the above described arrangement, the tension on the various belts may be easily and quickly adjusted. The tension in the belt 175 may be varied by adjusting the nuts 159, 160 and thereby pivoting the arms 181, 182. The tension of the belt 179 may be varied by adjusting the nuts 172, 173 and thereby pivoting the arms 161, 162.

The operation of the bowling machine may be summarized as follows: When the player wishes to play a game, he deposits a coin in the coin-operated switch mechanism 23, which supplies power to the machine for a predetermined period of time. Upon depositing of the coin, the switch mechanism 23 completes the circuit to the motor 153 which, through the pulley and belt arrangement, continuously rotates the pulley 151. This, in turn, continuously rotates pulley 93 of the pin-setting apparatus and the endless belt 130 of the ball-return apparatus.

Since some of the pins may have been displaced from a previous game, the player may initially reset the pins by pulling the hand lever 24. Pulling the hand lever 24 will pull the cable 92 toward the player's station, tending to pivot the lever bar 90 on its journal bearing 91 (Fig. 2). Pivoting of the lever bar 90 will, in turn, tend to move the platen 64 downwardly through connecting members 89, lever 88, shaft 83, arms 82 and links 80.

Pulling of the cable 92 will also bring it into frictional engagement with the continuously rotating pulley 93, which is rotating in such a direction as to facilitate movement of the cable 92, thus boosting or enhancing the force with which the platen 64 is lowered. However, the rate at which the platen 64 is lowered is controlled by the dash pot 96 acting upon the platen 64 through the dash pot arm 97 and link 98. Lowering of the platen 64 causes the flexible lips 104 of the resilient material surrounding each opening 65 of the platen to deflect upwardly when the pins are deposited onto the alley. Releasing of the hand lever 24 will cause the platen to return to its original position above the alley under the action of the weight 86. The upward movement of the plate 64 is limited by chain 100, any shock involved being absorbed by spring 101.

The player may then roll one or more bowling balls down the alley. Any pins 57 that are struck by the ball will be disengaged from their magnets 55 and will be raised by the weights 63 into the openings 65 in the platen. The bowling ball will roll toward the rear of the alley down the inclined section 106 to the transverse ramp 107 which will guide the ball onto the short inclined section 141 of the chute and under the endless belt 130. The ball will then be carried up the inclined section 142 of the chute to the top thereof. The ball will then roll down the track 180 and return to the player's station. Positive movement of the ball out of the chute 140 is insured by the short section 148 which acts as a kicker on the ball.

The tension on the belt 179 may be varied by adjusting the nuts 172, 173 and thereby pivoting the downwardly

extending arms 161 and 162 on which journal bearings 165 and 166 are mounted. The tension on the belt 175 may be varied by adjusting the nuts 159, 160 and thereby pivoting the arms 181 and 182.

It can thus be seen that I have provided an apparatus which utilizes a single means for facilitating the movement of the platen to pin-setting position and, in addition, for driving the ball-return apparatus. The movement of the platen to pin-setting position is controlled by a dash pot to insure the positive positioning of the pins without damage to the linkage. The ball-return apparatus is simply constructed and provides for a positive return of the balls to the player's station. The pin-setting apparatus and the ball-return apparatus are mounted on a unitary frame whereby the entire frame may be removed from its position relative to the alley merely by disconnecting the electrical connections to the coin-operated switch mechanism 23, disconnecting the end of the cable 92 from the lever bar 90, and removing the frame with the pin-setting apparatus and the ball-return apparatus mounted thereon from its position overlying the pin-setting platform. The backstop 105 may also be quickly and easily removed.

I claim:

1. A bowling machine comprising a substantially horizontal alley having a player's station at one end thereof and a pin-setting platform at the other end thereof, means mounted for releaseably holding bowling pins on said alley, a multiplicity of bowling pins adapted to be releaseably held by said holding means, a platen mounted for vertical movement above said pin-setting platform, means for urging said platen upwardly, a cord attached to each said pin at the upper end thereof, means attached to each said cord tending to move said pin upwardly toward said platen when it is struck by a bowling ball and moved out of position on the pin-setting platform, manually operated means connected to said platen and extending to the player's station for lowering the platen for resetting the pins, and power operated means responsive to the operation of said manual means to assist the lowering of said platen, said manually operated means comprising links pivotally connected to said platen, arms pivotally connected to said links, a horizontal shaft mounted for rotation about its axis, said arms being fixedly connected to said shaft, a lever fixed to said shaft and extending rearwardly thereof, a lever bar pivotally mounted intermediate its ends about a fixed point above said lever, connecting members pivotally connecting the end of said lever and one end of said lever bar, a cable connected

to the other end of said lever bar and extending forwardly of the alley to the player's station, a hand lever, the other end of said cable being attached to said hand lever, said power operated means comprising a pulley, means for continuously rotating said pulley, said pulley being positioned to be frictionally engaged by said cable when the hand lever is pulled thereby facilitating the movement of said cable, the movement of said cable causing said lever bar and lever to rotate and, in turn, causing the shaft to rotate moving the arms downwardly and lowering the platen.

5 2. The combination set forth in claim 1 wherein said means for urging said platen upwardly comprises an arm fixed to said shaft and extending rearwardly from said shaft, and a weight mounted on said latter arm.

10 3. The combination set forth in claim 2 including means for limiting the upward movement of said platen comprising a flexible element extending between a fixed point and said arm to which the weight is attached.

20 4. The combination set forth in claim 3 including a yieldable element extending between the flexible element and said fixed point for absorbing any shock occurring as a result of limiting the upward movement of the platen.

25 5. The combination set forth in claim 1 including means for controlling the rate of movement of said platen downwardly.

30 6. The combination set forth in claim 5 wherein said means for controlling the rate of movement comprises a dash pot mechanism acting on said means for lowering said platen.

7. The combination set forth in claim 6 wherein said dash pot mechanism is connected to said arm on which said weight is attached.
